JOHN WARREN VEDDER, FREDERICK W. LODDING, AND GEORGE LAMOUREUX, OF WORCESTER, MASSACHUSETTS, ASSIGNEES TO RICE, BARTON & FALES, INC., OF WORCESTER, MASSACHUSETTS, A CORPORATION OF MASSACHUSETTS

FOURDRINIER MACHINE

Application filed February 8, 1926. Serial No. 86,744.

This invention relates to a paper making machine of the Fourdrinier type. The principal objects of the invention are to provide an improved arrangement by which 5 most of the parts that are in the way can be removed sideways as a unit to permit the Fourdrinier wire to be inserted as a whole; to provide various improvements in the several parts of the machine by which this is 10 accomplished, particularly a pit under the machine for receiving a pivoted track, extending across the wire and the pit, adapted to support rolls carrying the removable frame and capable of being swung back out of the 15 way at one side of the pit so as to allow the wire to be inserted; to provide an improvement in the mounting of the lower couch roll so that it will not have to be removed but can be simply shifted back and forth when the 20 wire is to be inserted; to provide a wire stretching device which also can be moved down entirely out of the way until the wire is in place ready to be stretched; to provide improvements in the arrangement for shaking 25 or vibrating the breast roll readily detachable to permit of its removal; to provide an arrangement whereby the frame can be lifted at one point to release it from its supports, and in general to provide a series of 30 improvements co-operating with each other for facilitating the replacement of the long Fourdrinier wire. Other features of the invention will appear hereinafter.

Reference is to be had to the accompanying 35 drawings, in which

Fig. 1 is a side view of one end of a paper making machine constructed in accordance with this invention in condition for use;

Fig. 1^a is a side view on reduced scale showing 40 the wire in running position but without the deckle mechanism;

Fig. 2 is a similar side view showing the machine with the frame removed and the wire in place ready for reassembly;

Fig. 3 is a plan of the wire stretching device for tightening up the wire;

Fig. 4 is an end view, partly in section, of one end of the machine, showing the mechanism for vibrating the breast roll and table rolls;

Fig. 5 is a plan of one of the pivoted rails for supporting the rear wheels of the carriage which have to be rolled out when the wire is to be changed; and

Fig. 6 is a sectional view on the line 6—6 55 of Fig. 5, showing the carriage in place.

We have chosen a well known type of machine for illustration to show the application of these improvements thereto. The invention involves several improvements in the parts thereof co-operating with each other and with the previously known constructions. The machine is illustrated as having a unitary frame 10, preferably formed of structural shapes, for supporting the various removable parts. This is located in front of the head box 11 which may be of the usual construction. Adjacent to this head box on the frame is the usual breast roll 12 just above which is the apron board 13 which is adapted 60 to swing upwardly and is supported by pivoted brackets 14 arranged to swing outwardly.

The deckle strap 15 is supported by deckle wheels 16 mounted in brackets detachably supported by the frame 10 in the usual manner. This invention does not relate to any features of the deckle mechanism and the usual constructions are shown co-operating with it. These include two slices 18 to 19 65 with adjusting means for controlling the passage of the solution and the thickness of the deposit on the Fourdrinier wire 20.

The Fourdrinier wire, of course, passes from the breast roll 12 to the couch roll 21. 75 It will be understood by anyone skilled in the art that this wire is endless and that according to modern practice it is intended to be put on this machine as a whole and not fed in and threaded through the machinery. For this purpose the foundation or floor on which the machine frame 10 rests is provided with transverse single tracks 22 80 on the front side of the machine and these tracks extend clear up to a pit 23 below the floor level over which the frame 10 is located. Adjacent to the pit are brackets 24 at the ends of the tracks 22, each provided with a vertical pivot pin 25 on which a track section 26 is carried. This is a piece of struc- 85

90 95 100

tural section, usually, with a track formed on its upper surface and adapted to swing from the dotted line position shown in Fig. 5 to the full line position in which it extends clear across the pit. On the opposite end of the swinging rail 26 it is shaped to fit against a short track section 27 fastened in the floor opposite the track 22. It has a removable pin 28 for connection with the rail 26.

10 It is clear therefore that this rail section can be swung across the pit so as to support the real wheel 29 of a pair when the frame 10 on which these wheels are located is moved out in the direction of the arrow in Fig. 6. 15 Then when this frame is entirely removed so that the rear one of the wheels 29 rests on the track 22, the track section 26 is disconnected at 28 and swung into longitudinal position, shown in dotted lines in Fig. 5. In 20 this case we have shown two sets of these wheels 29 on downwardly and outwardly extending brackets 30, but of course some other number can be employed.

25 The frame 10 supported by the wheels carries the table 31 by means of flat springs 37 which allow the table to vibrate, being supported from the bottom and having a space at each side. Between two adjacent springs 37 the spaces between the channel irons of 30 the frame 10 are filled by cast iron blocks 39^a to increase the rigidity of the frame. The table 31 is pivoted on a vertical pivot 32 at one end, in the form shown, and carries the table rolls 33 thereon all in one section. This 35 table is pivotally connected at 34 with the bearings 47 of the breast roll 12 and therefore when the breast roll is vibrated transversely of the machine the table with its rolls 33 will be vibrated with it at that end 40 about the pivot 32 at the other end. This table has below it a series of plates or chutes 35 which drain the liquor passing down between the rolls into a series of troughs 36 carried by the frame 10, directing all this 45 liquor into the several troughs 36. The liquor from these troughs is drawn off and used over again as usual and the plates 35 are so placed that at all points there is something to catch the water. The usual suction boxes 38 are also mounted on the frame 50 10.

At the entrance end of the machine is a power shaft 40 which, by means of an adjustable crank 41, swings a bell crank 42 about a center 43 and vibrates a flexible rod 44 longitudinally. This rod has a head 45 which is perforated to receive a pin 46 that is mounted on a bearing 47 of the breast roll 12. This bearing 47, as well as the opposite bearing, is supported by a series of thin vertical flexible plates 49 held fixed at the bottom between a pair of channel irons 50 on the frame 10. This permits vibration of the roll 12 from the shaft 40 in a direction lon-

itudinal with respect to the roll but transverse with respect to the machine. It moves on a guide 39. The supports 50 are mounted on downwardly extending projections at the head end of the frame 10. Of course this frame must be supported so as not to receive vibration from the shaft 40. Stationary brackets 51 are provided on opposite sides at the head end, each having an overhanging end for receiving a vertically movable pin 52. A locking lever 53 is employed on the overhanging end of the frame 50 at each side to lock this pin with respect to the standard 55.

Furthermore, at this end of the machine there is a screw 54 at each side with a worm and hand wheel arrangement 55 for raising the frame 10 at this end and adjusting it to the proper height. This is used to lower the frame on its wheels.

Located at a distance from this adjustment is another adjusting arrangement for tightening the Fourdrinier wire. This comprises a transverse stretch roll 56 and two vertical screws 57 operated through bevel gears by a hand wheel 58 for the purpose of moving the stretch roll 56 up and down. The screws 57, through the use of the removable hand wheel 58, raise and lower the supporting bearings for the roll 56. The supporting bearings move up and down in stationary frames 59, being carried by guides 60 therein.

The use of this machine is making the paper is substantially the same as any paper making machine of this type. The Fourdrinier wire 20 passes as usual over the breast roll 12 and the couch roll 21, the latter being mounted on a frame 61 which moves back and forth on a track 62 by a rack and pinion arrangement 63 which can be operated by hand or power for the purpose of slackening the Fourdrinier wire. This wire of course passes over the table rolls 33 and under some of the wire rolls 65 which are mounted on the under side of the frame 10 and move with it. Below it is supported by the wire roll 65 near the couch roll and by the tightening roll 56 which has been described and which is moved up and down to affect the tension of the Fourdrinier wire. Normally the screws 54 are turned so that the frame 10 rests on them and on a pivot rod 69 at the other end of the machine. This rod carries supports 68 having sockets for projections 67 at the end of the frame 10.

When it is desired to replace the wire, the old wire is cut and removed in the usual way, then the first thing that is done after removing the old wire is to lower the roll 56 down to the lowermost position, below the bottom of the pit indicated in Fig. 2. Now the couch roll 21 is moved up to the position in Fig. 2. This gives the necessary slack for putting on new wire. The pin 46 is removed to release the breast roll. The hand wheels 55 and 58

are removed. Of course it is understood that at this time the rails 26 are located longitudinally as shown in dotted lines in Fig. 5. The deckle strap mechanism is moved upwardly, as is well understood, by any kind of lifting device.

Now the fastening device 53 is released, the pin 52 taken out, the rails 26 are swung across to the position shown in full lines in Fig. 5 and the wheels 55 restored. The screws 54 are adjusted to lower the table to rest on the wheels 29. The lowering of the screws 54 on account of the support of the frame 10 on the wheels 29, raises the extreme opposite end 15 of the table so that the projection 67 comes out of the socket 68 which releases the frame 10 from this pivotal support. Now the parts are in the position shown in Fig. 2, all ready to permit of the moving of the frame 10 with 20 all its supported parts out sideways to the front so that the rear wheels 29 rest on the track 22 instead of the track 27.

Now the rails 26 are swung back to longitudinal position. The new wire is first inserted over the couch roll in the usual way 25 and is placed in the machine in the position 20'. The poles 66 are inserted to hold the wire in position. Then the rails are swung across the pit and the frame 10 is moved back 20 into its original position. There is no obstacle to this motion at this time.

This constitutes a simple way of applying the Fourdrinier wire with comparatively few parts of the machine to be handled separately and consequently a comparatively small amount of preparation for this operation. Furthermore, the parts of the machine which are moved out together can be so moved without disturbing any of the adjustments 40 except the two adjustments mentioned and can be put back again in just the same position without any undue amount of labor. This arrangement does not interfere with the vibrating of the breast roll and the adjacent 45 end of the table, but on the other hand, this is arranged for in a very simple way. The several features of the invention above described all co-operate to secure the desired results, and constitute a part of the means by which they are accomplished. These arrangements, designed as they are for the facilitation of the application of the Fourdrinier wire, add little, if any, to the expense of the machine and reduce the difficulty of 50 making this change.

Although we have illustrated and described only a single form of the invention and shown it as applied to only one type of paper making machine, we are aware of the fact that modifications can be made therein by any person skilled in the art without departing from the scope of the invention as expressed in the claim.

Therefore we do not wish to be limited in 55 these respects but what we do claim is:—

1. In a Fourdrinier machine, the combination of a frame, wheels at the floor level for supporting said frame, said frame being movable sideways on said wheels to permit the Fourdrinier wire to be exchanged, a couch roll supported beyond said frame at the end, and means for moving said couch roll horizontally toward and from the frame to give the Fourdrinier wire slack when the frame is in position within the Fourdrinier wire. 70

2. In a Fourdrinier machine, the combination with a frame for supporting the table rolls and suction boxes, wheels thereon by which it is movable sideways, tracks for said wheels, a pivot at one end of the frame, a detachable connection between the frame and said pivot, and an adjusting device at the other end of the frame, said wheels being so located that when the frame is lowered by the adjusting device so that the wheels rest on the tracks, the other end of the frame will be 80 lifted thereby to release said detachable connection.

3. In a Fourdrinier machine, the combination of a frame having guide rolls for supporting and guiding a Fourdrinier wire thereon, a horizontal pivot at one end of said frame, a detachable connection between said pivot and the frame at that end, whereby by raising that end of the frame it will become 90 detached from the connection, wheels for supporting said frame at a distance from each end, and means whereby when the frame is lowered so as to rest on the wheels it will become detached from the pivot and can be 95 rolled out of position on the wheels. 100

4. In a Fourdrinier machine, the combination of a frame having a breast roll at one end and guide rolls for supporting and guiding a Fourdrinier wire thereon, a horizontal pivot at one end of said frame, a detachable connection between said pivot and the frame at that end, whereby by raising that end of the frame it will become detached from the connection, wheels for supporting said frame at a distance from each end, and means for vertically adjusting the opposite end of the frame to a position in which the wheels will clear the floor to a position in which the connection at the pivot end will be detached, 110 whereby when the frame is lowered so as to rest on the wheels it will become detached from the pivot and can be rolled out of position on the wheels. 115

5. In a Fourdrinier machine, the combination of a frame having guide rolls for supporting and guiding a Fourdrinier wire thereon, a horizontal pivot at one end of said frame, a detachable connection between said pivot and the frame at that end, whereby by 120 raising that end of the frame it will become detached from the connection, wheels for supporting said frame at a distance from each end, and means whereby when the frame is lowered so as to rest on the wheels it will be 130

come detached from the pivot and can be rolled out of position on the wheels, with means for fixedly holding the frame at the end.

5 6. In a Fourdrinier machine, the combination with a fixed frame comprising two structural sections spaced apart, a flat spring fixed to the bottom thereof, extending up between them and above them, a vibratable frame 10 carried in part by said spring, and solid pieces inserted between said structural sections and filling the space, at points on either side of the spring.

15 In testimony whereof we have hereunto affixed our signatures.

J. WARREN VEDDER.
GEORGE LAMOUREUX.
